ARTHUR S. TAYLOR, OF CANTON, OHIO, ASSIGNOR OF ONE-HALF TO HORACE E. SMYTHE,
OF PITTSBURGH, PENNSYLVANIA.

CARBURETER.

1,247,602.

Specification of Letters Patent.

Patented Nov. 20, 1917.

Application filed December 19, 1916. Serial No. 137,774.

To all whom it may concern:

Be it known that I, ARTHUR S. TAYLOR, a citizen of the United States, residing at Canton, in the county of Stark and State of Ohio, have invented new and useful Improvements in Carbureters, of which the following is a specification.

My invention relates to carbureters.

The object of this invention is to produce a carbureter for explosive engines by the use of which gasoline or other light hydrocarbons suitable for forming explosive mixtures with air may be continuously drawn from a constant flow of the heavier hydrocarbon liquids, such as crude oil, for example, and mixed with the proper proportion of air. It is one of my objects to provide a suitably heated surface over which the crude oil may be evenly and continuously spread. Another object is to provide suitable means for removing from the said surface the residue which remains after the light explosive hydrocarbons have been extracted by the suction of the engine. Another object is to provide for the said residue a removable receptacle or collector which preferably forms a bottom closure of the carbureter and is provided with tubular openings serving as vacuum breakers for the carbureting chamber.

Referring to the accompanying drawings, Figure 1 is an elevation showing my improved carbureter and certain adjunctive apparatus; Fig. 2, a central vertical section of the carbureter; Fig. 3, a top plan view of the oil-heating cone, the oil-supply nozzle, the oil-distributer, and the scraper, the oil-supply pipe being shown in horizontal section; Fig. 4, a detail elevation showing the said cone and the means of securing it to the casing; and Fig. 5, a section on the line V—V, Fig. 2.

On the drawings, 1 represents the carbureter having at its lower end the chamber 2 which may be cylindrical. The lower portion 3 of this chamber is a residue collector or receptacle, detachably connected to the upper portion by the bolts 4 extending through opposing flanges on the two portions of the chamber 2. 5 represents a number of air-supplying vents or tubes, which extend up from the bottom of the receptacle 2 to the top of the receptacle or a little higher.

At the upper end of the chamber 2, I

arrange an oil receiving surface 6 shown in the present instance as a cone, having its apex extending upwardly and its base provided with outwardly extending lugs 7 which are secured by the screws 8 to the inwardly extending lugs 9 on the inner wall of the chamber 2.

The wall of the chamber 2 is tapered upwardly preferably parallel with the lateral surface of the cone, as shown at 10, to about the level of the top of the cone or a little higher, whence the said wall is continued upwardly in preferably cylindrical form, as shown at 11, whereby the upwardly tapering carbureting chamber or passage 12 is provided around the surface of the cone and a cylindrical passage 13 is provided above the cone. The walls 10 and 11 are surrounded by the double or jacketed wall 14 which conforms to the general shape of the walls 10 and 11, an air-passage 15 being provided between the wall 14 and the walls 10 and 11. The cylindrical portion of the wall 14 extends up above the top of the passage 13 to form the carbureting chamber 16 which is continued past the throttle 17 to a suitable receiver, as the intake manifold of an explosive engine, not shown. The lower end of the passage 15 is supplied through the pipe 18 with air which may be preheated, if desired. The pipe 18 is provided with the damper or valve 19 for regulating the influx of air into the passage 15. 20 is an auxiliary air-supply chamber opening into the chamber 16 near the top of the wall 11 and having the inwardly opening valve 21 yieldingly held closed by the spring 22 having its tension regulated by the nut 23. This auxiliary air-supply mechanism being well known needs no further description.

The cone 6 should be heated to promote the separation of the lighter explosive hydrocarbons from the heavy oil supplied to the surface of the cone in a manner to be explained presently. The cone may be heated by various means, as heated air or water, but I have shown it supplied by the electric heater 24 arranged in the interior of the cone.

25 is a vertical shaft extending up centrally through the cone 6. The upper end of the shaft extends through the hub of the spider 26 having the arms 27 on the interior face of the wall 11. The upper end of the shaft has an axial bore 28 which opens into

the chamber 26 and has at its lower end near the top of the cone 6 the nozzle 29 arranged with its delivery orifice over the cone close to its apex.

5 30 is a preheater or receptacle for the crude oil or other hydrocarbon to be supplied to the surface of the cone 6. This receptacle may be heated by electricity or hot water from the water jacket of an explosive engine 10 or by hot air from the exhaust thereof. I have shown a coil 31 surrounding the receptacle 30, through which electricity, hot water, or hot air may be supplied for preheating the crude oil. The preheated oil is drawn from 15 the receptacle 30 by the pump 32 which is connected thereto by the pipe 33. The pump forces the oil through the pipe 34 which passes through the carburetor above the connection 26 and extends through the upper 20 wall of the connection. The pipe 34 has the by-pass valve 35 which regulates the amount of oil passing above it through the pipe 34. This valve has the arm 36 by which it may be regulated. 37 is a by-pass pipe through 25 which oil, forced to the valve 35 and not allowed to pass to the nozzle 29, is returned to the preheater. The pump is driven by the shaft 38 by means of the gear 39 connected to a suitably driven shaft. The shaft 38 is 30 connected to the shaft 25 by the bevel gears 40.

The shaft 25 just above the top of the cone is provided with the oil-spreader 41 which travels in contact with the surface of 35 the cone and at the rear of the nozzle 29 for the purpose of spreading the oil over the surface of the cone. I prefer to curve the spreader backwardly so as to allow some of the oil to flow to the lower part of the 40 cone before the spreader engages it whereby the oil will spread over the cone from one end to the other.

I provide the shaft 25 just above the top of the cone with a scraper 42 which engages 45 the surface of the cone from top to bottom and scrapes from its surface the residue remaining from the crude oil after the lighter hydrocarbons have been drawn off.

Assuming that the chamber 16 is connected to the intake pipe of an explosive engine; 50 that the shaft 38 is connected to an engine shaft which varies in speed as the speed of the engine; that the cone 6 is suitably heated by the heater wire 24 or other means; 55 that the jacketed wall 14 is supplied by heated water or air; that the crude oil is properly heated by the coil 31; and that the engine is running, thereby creating a partial vacuum in the chamber 16, the pre-heated oil flows from the pipe 34 into the connection 26 and thence through the oil-supply passage 24 and the nozzle 29 and upon the upper end of the heated cone. The 60 rotating shaft 25 causes the spreader 41 to 65 spread the oil over the cone behind the nozzle 29 and the scraper 42 to scrape off ahead of the nozzle such residue as may remain thereon, the residue dropping into the collector 3. At the same time the suction of the engine cylinders is drawing up through 70 the chamber 16 the gasoline and other light explosive hydrocarbons extracted from the crude oil on the cone, sufficient air passing 75 through the vacuum-breaking pipes 5 to cause the suction of the engine cylinders to 80 exhaust the light hydrocarbons from the chamber 12. The suction of the engine cylinders also draws air through the main air-supply pipe 18 and the chamber 15 to provide the hydrocarbon gas passing up the 85 chamber 16 with sufficient air to make the proper explosive mixture for the slower engine speeds. The suction of the engine opens the auxiliary air-valve 21 to supply additional air for higher engine speeds. 85

The various valves all have external adjusting means which may be operated from a single point, as the dash of an automobile. The collector 3 may, from time to time be disconnected from the upper part of the 90 chamber 2 and lowered so that the said residue may be removed.

I do not desire to be restricted to the details and combinations shown and described, as they may be variously changed 95 without departing from the spirit of my invention. For example, the oil heating surface 6 may obviously have many different shapes.

I claim—

1. In a carburetor, a heated surface, means for causing oil containing light hydrocarbons to flow on the said surface, a carbureting chamber in communication with the heated surface, means for supplying air to the said surface, and means for positively removing from the said surface the residue remaining after the lighter hydrocarbons have been extracted. 100

2. In a carburetor, a heated surface, means for causing oil containing light hydrocarbons to flow on the said surface, a carbureting chamber in communication with the heated surface, means for supplying air to the said surface, and a spreader for engaging the oil and distributing the same over the said surface. 110

3. In a carburetor, a heated surface, means for causing a constant supply of oil containing light hydrocarbons to flow on the 115 said surface, a carbureting chamber surrounding the said surface, an air-supply chamber surrounding the first chamber, a second carbureting chamber to receive the carbureted hydrocarbons from the first 1 chamber, and means for positively removing from the said surface the residue remaining from the oil after the lighter hydrocarbons have been extracted. 120

4. In a carburetor, a heated surface, a 1

5 nozzle arranged to discharge upon the said surface a constant supply of oil containing light hydrocarbons, means for producing relative rotation of the surface and the nozzle, a carbureting chamber surrounding the surface, a second carbureting chamber connected to the chamber, and means for positively removing from the said surface during the said rotation the residue remaining

10 from the oil after the lighter hydrocarbons have been extracted by the exhaust.

5. In a carbureter, a heated surface, a nozzle arranged to discharge upon the said surface a constant supply of oil containing light hydrocarbons, means for producing relative rotation of the surface and the nozzle, a carbureting chamber surrounding the surface, a second carbureting chamber connected to the chamber, means for supplying air to the chamber, means for positively removing from the said surface during the said rotation the residue remaining from the oil after the lighter hydrocarbons have been extracted by the exhaust, and

25 means at the rear of the nozzle for spreading the oil over the said surface.

6. In a carbureter, a heated surface, a nozzle arranged to discharge upon the said surface a constant supply of oil containing light hydrocarbons, means for producing relative rotation of the surface and the nozzle, a carbureting chamber surrounding the surface, a second carbureting chamber connected to the chamber, means for supplying air to the chamber, and means at the rear of the nozzle for positively spreading oil over the said surface.

7. In a carbureter, a heated surface, a nozzle arranged to discharge upon the said

surface a constant supply of oil containing light hydrocarbons, means for producing relative rotation of the surface and the nozzle, a carbureting chamber surrounding the surface, a second carbureting chamber connected to the chamber, means for supplying air to the chamber, and means at the rear of the nozzle for spreading oil over the said surface, the spreading means having the parts thereof trailing more and more behind the nozzle as their distance from its center of rotation is greater.

8. In a carbureter, a stationary heated surface, a rotary vertical shaft extending through the same, a nozzle secured to the shaft and arranged over the said surface, a carbureting chamber around the said surface, means for supplying air to the chamber, a pump for delivering to the nozzle a constant supply of oil containing light hydrocarbons, and means for varying the rate at which the oil is delivered to the nozzle.

9. In a carbureter, a stationary heated surface, a rotary vertical shaft extending through the same, a nozzle secured to the shaft and arranged over the said surface, a carbureting chamber around the said surface, means for supplying air to the chamber, a second carbureting chamber connected to the said chamber, a pump for delivering to the nozzle a constant supply of oil containing light hydrocarbons, and means for driving the pump and shaft and for varying the rate at which the oil is delivered to the nozzle.

Signed at Pittsburgh, Pa., this 8th day of December, 1916.

ARTHUR S. TAYLOR.
